UNITED STATES PATENT OFFICE.

CHARLES S. BURTON, OF OAK PARK, ILLINOIS, ASSIGNOR TO EMIL TYDEN, OF HASTINGS, MICHIGAN.

EXTENSION-TABLE LOCK.

No. 901,951.

Specification of Letters Patent.

Patented Oct. 27, 1908.

Application filed June 10, 1907. Serial No. 378,990.

REISSUED

To all whom it may concern:

Be it known that I, CHARLES S. BURTON, a citizen of the United States, residing at Oak Park, in the county of Cook and State 5 of Illinois, have invented new and useful Improvements in Extension-Table Locks, of which the following is a specification, reference being had to the drawings forming a part thereof.

10 The purpose of this invention is to provide an improved device for locking together the parts of an extension table, especially adapted for so locking the table, not only when fully closed but at any point to which 15 it may be extended, with interposed leaves or fillers.

It consists in the features of construction shown and described and set out in the claims:

20 In the drawings:—Figure 1 is an inverted partly sectional plan view of a table embodying this invention, section being made at a horizontal plane through the pedestal. Fig. 2 is a section at the line 2—2 on Fig. 1. Fig. 3 is a partly sectional side elevation with the top and skirt or marginal molding partly cut away. Fig. 4 is a view similar to Fig. 2, showing the operating pawls in disengaged position. Fig. 5 is a section at the 25 line 5—5 on Fig. 1, with the pawl in a different position. Fig. 6 is a detail section at the line 6—6 on Fig. 1. Fig. 7 is a section at the line 7—7 on Fig. 1.

I have shown this invention applied to a 30 pedestal extension table because this form of table presents some difficulties which are not present in the ordinary form of five-legged table, but it is to be understood that the invention is applicable to any extension table 35 employing the customary extension slides.

The two table members, 1 and 2, are represented as connected by customary slides, which are shown in sufficient number to indicate the manner of using the invention 40 with any number. It will be understood that the minimum number of slides in each of the two sets of slides in any extension table is three, the middle slides, 3, 3, of each set being connected by a bridge, 4, which 45 carries the center leg, 5. The outermost slides, 6, 6, of the two sets are made rigid with one member of the table top,—in this case with the member, 1,—while the innermost slides, 7, 7, are similarly rigid with the 50 other table member, 2. The corresponding

intervening slides in the two sets may be unconnected with any parts, except for their sliding connections with the adjacent slides, and when this is the case the application of my invention presents the least difficulties, 60 but in case of a pedestal table, the pedestal caps, 8, 8, of the two pedestal members, 9, 9, constitute bridges for attaching the pedestal members respectively to the table members. Such attachment in the more common type of pedestal table is direct,—that is, so as to make the pedestal member rigid with the corresponding table member,—the bridges, 8, 8, being made rigid, one with the outermost slides, 6, 6, and the other with the 65 innermost slides, 7, 7, which are rigid with the two table members respectively. For certain construction in which it is desired to render the table top extensible to a certain extent without extending the pedestal as 70 shown in the drawings of this application, the pedestal caps or bridges, 8, of one pedestal member are connected to the slides, 9^a, 9^a, which intervene between the outermost and the middle slides, and the corresponding 75 bridge of the other pedestal member is connected to the slides, 10, 10, which intervene between the innermost and the middle slides. When any larger number of slides is employed they will usually intervene between the middle slide and the next slide on either side. To enable the operating pawl fingers, 18, hereinafter described, to reach the edges 80 of the slides, 9^a, and the pawl fingers, 20, hereinafter described, to reach the edges of 85 the slides, 7 and 10, the attachment of the bridges, 8, 8, to the slides, 9^a and 10, respectively, is made by angle plates, 35 and 36, the plate, 35, being let into the upper surface of 90 the longer bridge, 8, and into the inner side 95 of the slide, 9^a, leaving nearly the entire thickness of that slide exposed at the edge for engagement with the pawl, as hereinafter described, the plate, 36, being similarly 100 let into and secured to the under side of the shorter bridge, 8, and extended beyond the end of said shorter bridge under the lower edge of the slide, 7, and let into and secured to the inner surface of the slide, 10, as seen 105 in Fig. 6.

On the under side of the bridge, 4, which carries the center leg there is mounted a rock shaft, 12, which, when thus mounted, extends through the center leg or past its upper end at its junction with the bridge, 4. At each 110

end of the rock shaft which extends past the lower edge of the outermost slides it is provided with a crank arm, 13, both cranks extending toward the right hand for operating the locking devices of the right-hand member of the table, and on the rock shaft inside of the innermost slides respectively there are provided two similar crank arms, 14, 14, extending in the opposite direction for operating the locking devices for the left-hand table member. To each of the crank arms, 13, 13, there are pivotally connected pawls, 15, 15, provided with means, as, for example, counterweights, 16^a, operating to uphold the pawls toward the plane of the table. Each pawl has at its end remote from the crank an inwardly jutting stud or finger, 18, which extends across the lower edges of all the slides outside the middle slide. To the crank arms, 14, there are connected similar pawls, 19, 19, which extend outward from the cranks alongside the innermost slides and have outwardly jutting fingers, 20, 20, extending across below the lower edges of all the slides located inward from the middle slides. The lower edges of the slides outside the middle slides are provided with ratchet teeth, 22, 22, having their abrupt shoulders facing toward the outer end of the table member to which the slides pertain in position to be engaged by the studs or fingers, 18, of the pawls, 15, for resisting the outward or extending movement of the slides, and for drawing the slides inward when the links are pulled inward. The notches in the several slides are separated by intervals equal to half the unit filler width, the fillers, 25, being all of the same width, and in the drawings they may be understood as about nine inches in width each, making the distance between ratchet teeth $4\frac{1}{2}$ inches. The inner slides similarly have their lower edges provided with ratchet teeth, 22^a, similarly spaced.

When the table is closed up without extension, the ratchet teeth are in position to be engaged by the fingers, 18 and 20, respectively of the pawls which are operated by the several cranks of the rock shaft, and the shaft being rocked in direction to carry the cranks respectively to the opposite side of the axis of the shaft from that to which the pawls from the respective cranks extend, the pawl fingers are engaged with the ratchet teeth, and if the table members are not tightly closed together the completion of the rocking movement of the shaft to the position at which the crank wrists are alined with the pawl fingers at the opposite side of the rock shaft therefrom will draw the table members tightly together, and the crank wrist having been carried the slightest degree beyond that position, the parts become locked, because any pull on the table members tending to separate them would

tend to rock the shaft further in the direction in which its rocking movement is prevented by the pawls, 19, which at that position are stopped against the bridge, 4.

When it is desired to extend the table, the shaft being rocked in the opposite direction first thrusts the pawls outward, carrying their fingers back from the ratchet teeth of the slides, and a little less than a half revolution of the rock shaft being made in this reverse direction the pawls are thrust out in line with their cranks. The pawls, 15, are stopped against further change of angle with respect to their cranks by studs, 26, which jut off from short extensions, 27, of the cranks and collide with the upper edges of the pawls respectively at the point of greatest extension or outward thrust thereof, and carry them downward, taking the fingers, 18, out of the path of the ratchet teeth of the slides. For effecting a similar result with respect to the pawls, 19, connected with the cranks, 14, there is provided a trip finger, 28, on a bracket, 29, mounted on the under side of the center leg bridge, 90 and with this trip finger the pawl collides at the same time in the rocking of the shaft that the studs, 26, collide with the pawls, 15, and this collision causes the further movement of the crank by carrying the inner end of the pawls upward, to tip the outer ends downward for disengagement of their fingers, 20, from the notches of the slides.

The rock shaft, 12, has an operating arm, 30, at one end terminating in a crank handle, 31, said arm being conveniently forged onto the pawl extension, 27, and appearing as a continuation thereof back past the end of the shaft, as seen in Figs. 1 and 3.

105

I claim:—

1. In an extension table, in combination with the extensible table top members, the sets of slides which connect them for extension consisting each of a middle slide and exterior and interior slides, the extreme exterior and interior slides being connected to the opposite table members and adapted to be withdrawn in opposite directions from the middle slide, the fillers adapted to be inclosed between the table top members when extended, and means carried by the middle slides for disengageably engaging the other slides at intervals corresponding to the width of the fillers.

2. In an extension table, in combination with the separable table members, the sets of slides which connect them for extension consisting each of a middle slide and slides at opposite sides of such middle slide, the extreme slides at each side being connected respectively to the opposite table members and adapted to be withdrawn in opposite directions from the middle slide; a rock shaft carried by the middle slides; pawls operated by the rock shaft, the extreme

110

115

120

125

130

slides having means for engagement of the pawls therewith for drawing and holding them in direction resisting extension.

3. In an extension table, in combination with the separable table members, two sets of slides connecting them for extension consisting each of a middle slide and slides in each set at opposite sides of the middle slides respectively, the extreme exterior and 10 the extreme interior slides being connected respectively to the opposite table members and adapted to be withdrawn in opposite directions from the middle slides; a bridge bar connecting the middle slides rigidly; a 15 rock shaft mounted on the bridge bar; two sets of pawls operated by the rock shaft engaging respectively the interior and exterior slides, said slides having devices for engagement of the pawls therewith to retract the 20 slides and resist extension thereof.

4. In an extension table, in combination with the separable table members, two sets of slides which connect them for extension, and fillers adapted to be interposed, each set 25 comprising a middle slide and exterior and interior slides at opposite sides of the middle slides respectively, all said exterior and interior slides being ratcheted, the step intervals between the ratchet shoulders being 30 half the unit filler width, and means carried by the middle slides coöperating with the ratchet shoulders for resisting extension.

5. In an extension table, in combination with the separable table members, the slides 35 which connect them for extension; a rock shaft carried by the middle slides having end cranks outside the outermost slides and intermediate cranks between the two sets of slides, said end and intermediate cranks being extended in opposite directions from

the shaft, the slides which are movable with respect to the middle slides for extension being ratcheted on their lower edges; pawls on the end cranks engaging the ratchets of the slides outside the middle slides, and 45 pawls on the intermediate cranks engaging the ratchets of the slides inside the middle slides.

6. In an extension table, in combination with the separable table members, slides for connecting them for extension and fillers adapted to be interposed; a rock shaft carried by the middle slides having extreme cranks outside the outermost slides and intermediate cranks inside the innermost slides 55 of the two groups, all the slides which move relatively to the middle slides for extension having ratcheted edges, the step intervals between the ratchet abutments being substantially half the unit filler width; pawls 60 on the intermediate cranks for engaging the ratcheted edges of the inner slides and on the extreme cranks for engaging the ratcheted edges of the outer slides, the cranks being of such length that their throw within 65 the range of rocking movement of the shaft is sufficient to actuate the pawls the ratchet step distance, the rock shaft having a range of rocking movement for carrying the cranks to locked position at opposite sides of the 70 rock shaft from that at which their pawls are engaged for locking the slides at retracted position.

In testimony whereof, I have hereunto set my hand at Chicago, Illinois, this 7th day of June, A. D., 1907.

CHARLES S. BURTON.
